BUILDING CONSTRUCTION

Iver M. Brandjord, Helena, Mont.

Application October 20, 1936, Serial No. 106,674

9 Claims. (Cl. 20—4)

This invention relates to improvements in wall constructions for buildings, and its objects are as follows:

First, to provide a corner construction that is primarily a separate part from the building itself, but so made that it can be incorporated as the building structure rises, the main purpose of said corner construction being to simulate a log cabin or log house, which purpose is accomplished to perfection when the outside walls are covered with what is known as log cabin siding.

Second, to provide a construction similar to that at the corners for defining the places where partitions come, and to break up the monotony of long walls, both the corner and partition structures involving the use of log units which are formed either to interlock with themselves or with some other part of the building framing.

Third, to make it possible to easily and cheaply imitate a log cabin or house, preserving all of the beauty and substantial appearance of a real log cabin or house without the necessity of using logs, and at the same time obtain the advantages of air spaces in the walls and all the other desirable features of frame construction.

Fourth, to use the foregoing corner construction with types of siding other than the mentioned log cabin siding, the foremost value of said corner construction being its superior durability and beautiful appearance as compared with other and known corner constructions, the secondary value of this combination lying in making the building appear as though it was an original log cabin, covered with planed siding throughout the wall space with the exception of the corners.

Other objects and advantages will appear in the following specification, reference being made to the accompanying drawings in which:

Figure 1 is a perspective view of a partially framed building, illustrating the attachable log cross corners and partition-wall log end projections, the ends of the siding entering the cut-outs in two adjoining log ends.

Figure 2 is a section taken on the line 2—2 of Fig. 1.

Figure 3 is a horizontal section taken on the line 3—3 of Fig. 1.

Figure 4 is a side elevation of one of the corner units.

Figure 5 is a plan view of the same unit.

Figure 6 is a vertical section taken on the line 6—6 of Fig. 1.

Figure 7 is a plan view of the cross log corner assemblage in Fig. 1.

Figure 8 is a perspective view similar to Fig. 1,

but illustrating a modification wherein each piece of siding enters a cut-out in a single log end.

Figure 9 is a vertical section taken on the line 9—9 of Fig. 8.

Figure 10 is a vertical section taken on the line 10—10 of Fig. 8.

Figure 11 is a detail perspective view of a further modification wherein the cut-outs of the log ends are beveled.

Figure 12 is a detail perspective view of a portion of siding, showing how it too is beveled to enter the foregoing cut-outs.

One of the main purposes of the invention as has been indicated already, is to enable the builder to erect an imitation log cabin or house, without having to go to the trouble and expense of obtaining the actual logs with which to build the walls. It should be understood that wherever "log" is referred to, a natural log is not necessarily meant. An elongated block of wood, whether of round or other cross sectional shape, fashioned to have the general appearance of a log, will be an acceptable substitute.

The cross log corners, as well as the partition-wall projections, are chiefly instrumental in carrying out the simulation, the effect being complete when the outsides of the walls are covered with log cabin siding. In a wall without partition wall projections, the ends of the siding applied on the wall are cut and fitted into the corner projections of the rectangularly abutting walls. In a wall with partition wall projections one end of each piece of siding is cut and fitted into the corresponding partition wall projection (Figs. 1 and 8).

Further details appear in the drawings to which reference is now made. Both modifications in Figs. 1 and 8 have common features, but consider Fig. 1 first. The building is generally indicated 1, and it is immaterial whether this is a cabin, house or other structure. The wall framing on one side, (the near side) is indicated 2, and that on the next side, 3. The framing 2 includes the extreme-end studs 4, 5, and the intermediate pair 6. Said pair has the side 7 of a door or other frame near it. The framing 3 includes studs of which 8 is the only one to which reference has to be made.

The cross log corner is generally indicated 9, and the log partition, 10. The corner 9 is built up as the structure progresses, and consists of units 11 which are laid upon and interlocked with each other in crossed relationship. All of these units are of identical construction with the exception of the bottom and top units which may have 55

to be cut as at 12, so that the description of one will answer for the others. The only distinction between the units of abutting walls is that the units of one wall, for instance the wall at 3, are turned over 180° from the positions in the other wall (indicated at 2), making an apparent but not actual right and left construction.

The unit 11 has a wall part 13 (Fig. 4), neck 14 and projection 15. The wall part is slabbed off or flattened at 16 (Fig. 5) in the vertical plane. This occurs on the outside of the unit, and its purpose is to provide a flat place on which to lay the siding 17 (Fig. 1) whether of the log cabin or other variety. The part slabbed off must correspond to the thickness and form of the siding itself, which is to take its place. The flat surface must be in alignment with the outside faces of the studdings in the building.

The neck 14 is cross-sectionally square, and its outside surface 17^a (Fig. 5) merges into the flattened place 16 at one side, and into a flare 18 at the other side. The inside of the unit 11 may be fashioned in any way desired, depending upon how the inside of the building is to be finished.

What may be called the inside surface 19 of the neck 14 (Fig. 5), inasmuch as it is opposite to 17^a, has an inwardly directed flare 20 on one side, and it communicates with what is, broadly, a cut-out 21 (Figs. 4 and 5) on the other side. The bottom 22 of this cut-out is flush with the surface 19 (Fig. 5). Its walls 23 are arc-shaped, and the double arcs which meet at the central point 24, form what is herein conveniently called a "double curve". The shapes of the matching double curves (Fig. 2) must correspond exactly to the shape of the siding which they receive. When a number of units 11 are superimposed in wall-form, the arcs 23 will match in such a way as to provide a recess between adjoining units, as at 25 (Fig. 1), for the ends 26 of the siding 17 (see Fig. 6 also).

Usually the units 11 will be round, or substantially so, in cross section, or they may be elliptical as previously suggested. But whatever their form, the necks 14 will interengage (Fig. 6) in crossed relationship. The siding 17 is shiplapped or tongued and grooved at 27, 28 to interfit. The wall parts 13 are covered on the outside of the siding, and when the latter is secured by the nails 29, the projections 15 will look as though they are extensions of the siding, itself appearing as so many logs. The inner ends 30 of the units 11 are secured to the studs 5 and 8 (Fig. 1) in any desired way, generally by nails.

Now as to the log partition 10. This consists of units 31 which are laid upon each other in a single plane (Fig. 1). Each partition unit has a wall part 32, neck 33 and projection 34. The neck is formed by diametrically opposite stud-spaces 35 (Fig. 3) with which the stud pair 6 is interlocked as shown. The units 31 are stacked between the studs 6. The neck 33 adjoins a cut-out 36 (Fig. 2), as in the instance of the neck 14 and cut-out 21 of the corner unit.

The cut-out 36 is duplicated on each side of the projection 34 (Fig. 3), and goes in deeply as at 37. Its walls 38 are arced (Fig. 2), coming together at a central point 39. The recesses 40 (Fig. 1), resulting from the cut-outs being matched when the units are stacked, receive the ends 41 of the siding precisely as before. The same numeral 29 indicates the nails by which the siding is secured to the studs 6.

So far it will be clear that the siding 17 lines up with the division between the units 11 and 31 of

the corners 9 and partition 10. This is the truest simulation of an actual log cabin. In Fig. 8 the simulation is not quite so good, but the structure here is adapted to simpler and cheaper steps of manufacture. Identical reference characters are used for corresponding parts in Fig. 1, only having the exponent letter *a* added for distinction.

The neck 14^a, now referring to only one unit 11^a, adjoins a single-arched wall 42. This is centered with respect to the neck, so that when the end 26^a is inserted in the recess the siding 17^a, of which the end, obviously, is a part, will stand in line with the projection 15^a, and will not be crossed as before. But the sidings 17^a are centered upon the division lines between the wall 15 parts 13^a, as at 43 (Fig. 8), and this makes the joints extra secure.

The same distinction as to the recess for the siding ends at the partition 10^a occurs at 44 (Fig. 9). Each recess is centered upon the projection 34^a, and so is each siding 17^a. Otherwise the arrangement is the same as that already described.

In Fig. 11 the arrangement is on the order of that in Fig. 8, insofar as it concerns the siding 25 running in line with the projections. Corresponding numerals are again used for identical parts, only adding the exponent letter *b*. The cut-outs 45 (functionally the same as 36 in Fig. 2 and 44 in Fig. 9) are mere inward bevels. Each 30 piece of siding 17^b is similarly beveled at 46 (Fig. 12) to match. Figs. 11 and 12 illustrate the corner structure, but the arrangement at the partition (not shown) will agree.

It should be noted that the log cross corners 35 and partition projections do not apply to any particular kind of siding, although they will be most useful in connection with the so-called log cabin siding shown. The recesses or cut-outs in the log projections must in all cases be 40 fashioned to suit the cross section of the siding adopted, and in practice the contour of the cut-outs may therefore be any one of a variety of forms and otherwise than circular as shown.

I claim:

1. A building having adjacent walls each of which has a framing, the framing of each wall being spaced at the corner, a corner construction consisting of crossed, interlocked and socketed log units secured to the respective framings in 50 continuation of the respective walls and resembling the log ends of a log cabin, and sidings attached to the framing having their ends projected into the sockets.

2. A building having adjacent walls each of 55 which has a framing, the framing of each wall being spaced at the corner, and a corner construction incorporated in the building in the corner space consisting of two tiers of log units, the units being crossed and the tiers being in 60 continuation of the respective walls, said units having cut-outs forming necks which interengage, said cut-outs including walls which form recesses when the necks are interengaged, and siding pieces attached to the framings of the walls 65 having their ends socketed in the recesses.

3. A building having adjacent outside and partition walls, each with framing and the outside walls with siding, a construction incorporated in the building joining the outside and partition wall 70 framings and consisting of interengaged units, said units having recesses containing the ends of the siding.

4. A building having adjacent outside and partition walls, each with framing and the outside 75

walls with siding, superimposed log units in continuation of the various walls, providing a crossed corner construction and a partition wall projection, the projections of both the corner and partition having double-arched cut-outs providing recesses medially of the division lines between the units to contain the siding ends.

5. A building having adjacent outside and partition walls, each with framing and the outside walls with siding, superimposed log units in continuation of the various walls, providing a crossed corner construction and a partition wall projection, the projections of both the corner and partition having single-arched cut-outs providing recesses centered on the projections and being in line with the sidings to contain the ends thereof.

6. A building having adjacent outside and partition walls, each with framing and the outside walls with siding, superimposed log units in continuation of the various walls providing a crossed corner construction and a partition wall projection, the projections of both the corner and partition having necks with adjoining cut-outs, the cut-outs being beveled and the ends of the siding also being beveled to fit together.

7. A log unit for use in building construction, said unit comprising a wall part, a cross-sectionally non-circular neck, said wall part being slabbbed off on one side to merge with a non-cir-

cular surface of the neck, and a cut-out to receive the end of a length of siding.

8. A building having adjacent outside and partition walls, at least one of the outside walls including extreme-end studs and an intermediate pair of studs and siding secured thereto, adjacent extreme-end studs being spaced from each other at the corner, a corner construction in the space between said studs, consisting of log units in crossed and interlocked engagement, forming tiers in continuation of the respective outside walls, another tier of log units stacked between the stud pair and having necks interengaged with said studs, said tier of log units being in continuation of the partition wall, all of the log units having recesses containing the ends of the siding.

9. In a building, adjacent walls, each of which includes vertical studdings, a corner construction for the walls consisting of crossed and interlocked log units each of which is slabbed off on the outer side in a vertical plane and flush with the outer surface of the studdings, siding attached to the studdings to complete the walls, said siding extending into the corner construction and substantially corresponding in thickness to the slabbed off portions of the units, the projecting portions of the units having recesses containing the ends of the siding.

IVER M. BRANDJORD. 30
